BELT SANDER

Theodore B. Thomas and Virginia L. Brown,
New London, Wis.

Application April 24, 1953, Serial No. 350,966

8 Claims. (Cl. 51—135)

1

This invention relates to a novel form of belt sander and more particularly to a belt sander which is constructed to be utilized as a drill press attachment utilizing the power furnished by the drill press for driving the sanding belt including a pulley speed changer, which is conventional with drill presses, for varying the speed at which the belt will be driven to thereby increase the versatility of the sanding attachment.

Another object of the invention is to provide a belt sander including a drive pulley which is separate from the remaining parts of the sander attachment and supported by a drill chuck whereby endless sanding belts of different lengths may be interchangeably employed with the sander attachment.

A further object of the invention is to provide a sander attachment which readily adapts itself for sanding and dressing curved edges of different radii and which may also be employed for sanding and dressing other portions of work-pieces including corners of edges thereof, such as moldings.

Another object of the invention is to provide a sander attachment wherein tightening of the sander belt may be readily accomplished by merely shifting a supporting bedplate of the attachment relatively to a drill press table to which the bedplate is clamped.

Other objects and advantages of the invention will hereinafter become more fully apparent from the following description of the drawings, illustrating a presently preferred embodiment thereof, and wherein:

Figure 1 is a side elevational view, partly in section, showing the belt sander attachment in an operative position connected to a conventional change speed drill press;

Figure 2 is a top plan view of the sander attachment taken substantially along a plane as indicated by the line 2—2 of Figure 1;

Figures 3 and 4 are enlarged cross sectional views taken substantially along planes as indicated by the lines 3—3 and 4—4, respectively, of Figure 1;

Figure 5 is a central sectional view, partly in elevation, taken through the larger drive spindle of the sander attachment;

Figure 6 is a fragmentary vertical sectional view of a portion of the backing plate and the mounting thereof; and

Figure 7 is an enlarged fragmentary cross sectional view taken substantially along a plane as indicated by the line 7—7 of Figure 1.

Referring more specifically to the drawings, the

2

belt sander attachment in its entirety and comprising the invention is designated generally 10 and includes an elongated base plate 11 having a narrow extension 12 constituting one end thereof and which forms an extension of one side edge 13 of said base plate.

Said narrow end 12 is provided with a pair of transversely spaced upwardly extending apertured standards 14 to receive therebetween a portion of an elongated supporting member 15 which is pivotally supported on said standards 14 by a pivot pin 16 which extends therethrough and through a portion of the support 15, for rocking movement of said support in a vertical plane. A substantially semicircular end table 17 has a slotted bar 18 fixed to and depending from an underside thereof. A bolt of a bolt and wing nut fastening 19 extends through the slot of the bar 18 and through the outer end 20 of the rocking support 15 to detachably and adjustably mount the table 17 thereon.

The rocking support 15 is provided with an antifriction bearing 21, as best illustrated in Figure 7, which is mounted therein between the pivot 16 and its outer end 20 and in which is journaled the lower end of a small diameter belt spindle 22 which rises substantially perpendicularly from said support 15. A manually adjustable screw 23 is threaded downwardly through an inner end 24 of the support 15, inwardly of the pivot 16, and has a lower end which rests normally upon a part of the bedplate portion 12 to limit rocking movement of the support 15 in a clockwise direction as seen in Figure 1.

The inner straight edge of the end table 17 is provided intermediate of its ends with a notch 25 which is disposed around the spindle 22.

The bedplate 11 has a supporting post 26 fixed to and rising therefrom adjacent its side edge 13 and remote to the narrow bedplate end 12. The post 26 has flat sides disposed transversely of the bedplate 11 and has a bolt and wing nut fastening 27 extending therethrough. An elongated side table 28 has a slotted bar 29 fixed to and depending therefrom and disposed substantially intermediate of the ends thereof. The bar 29 extends downwardly on one side of the post 26 and the bolt of the fastening 27 extends therethrough for adjustably securing the bar 29 to said post for supporting the side table 28 thereabove.

A back or backing plate 30 has a pair of legs 31 secured to an inner or back side thereof by fastenings 32. The legs 31 extend downwardly from a bottom edge of the backing plate 30 and

terminate in right angularly turned longitudinally slotted foot portions 33 which extend away from the plane of the backing plate 30 and which rest on the base plate 11. Screw fastenings 34 extend loosely through the slots or foot members 33 and threadedly engage in the base plate 11 for securing the backing plate 30 above said base plate and in a vertical plane, and substantially longitudinally of the base plate. An outer face 35 of the backing plate 30 is spaced from the adjacent inner edge 36 of the side table 28. Said outer face 35 is shown provided with one groove 37 which extends from end-to-end thereof; however, the face 35 may be provided with one or more grooves of different cross sectional sizes and shapes, for a purpose which will hereinafter be apparent.

All of the parts previously described are directly or indirectly supported by the base plate 11. The wide end of said base plate, which is located remote to the narrow end portion 12 thereof, is adapted to rest on a portion of a table 28 of a conventional change speed drill press, a portion of which is illustrated at 39. Said base plate portion is secured to the drill press table 28 by a conventional clamp 40, adjacent the edge of the base plate which is located remote to said aforementioned edge 13.

A relatively large drive spindle or pulley 41, of a diameter substantially greater than that of the spindle 22, has an intermediate portion of a shaft or stem 42 extending centrally therethrough and secured therein. As best seen in Figure 5, the ends of the shaft or stem 42 extend from the ends of the spindle or pulley 41. One shaft end 43 is larger than the other shaft end 44. Said shaft ends of different diameters are adapted to fit drill chucks of different sizes, for adapting the pulley 41 to drill presses having chucks of different sizes. As illustrated in the drawings, the larger shaft end 43 is shown secured in a drill chuck 45 of the drill press 39, in a conventional manner, for suspending the pulley or spindle 41 therebeneath. An endless sanding belt 46 having an abrasive outer surface is trained around the pulleys or spindles 41 and 22 with one flight or reach thereof extending between the backing plate outer face 35 and the side table inner edge 36. This is accomplished before the clamp 40 is tightened so that after the belt 46 is in position as illustrated in Figures 1 and 2, the base plate 11 may be displaced from right to left away from the large spindle 41 and the clamp 40 is then tightened for securing the base plate 11 to the drill chuck table 38 with the belt 46 tensioned. By slightly loosening the clamp 49 and swinging the base plate 11 counterclockwise relatively to the clamp, as seen in Figure 2, additional tensioning of the belt 46 can be accomplished. The belt 46 can also be tensioned by advancing the screw 23 downwardly through the support end 24 rocking the support 15 counterclockwise on the pivot 16, as seen in Figure 1, to displace the spindle 22 away from the spindle 41. However, ordinarily this is not done but rather the screw 23 is adjusted so that the axis of the spindle 22 will be perpendicular to the base plate 11 and parallel to the axis of the spindle 41. The ends of the belt 46 are joined along a diagonal line 47, for a purpose which will hereinafter be described. It will also be apparent that belts 46 of different lengths may be employed, since the distance between the spindles 22 and 41 may be varied substantially as the spindle 41 is supported independently of the base plate 11.

11. The peripheries of both spindles or pulleys may be provided with a suitable non-slip coating, as indicated at 48 in Figure 5 in reference to the spindle 41. Likewise, the diameters of the spindles can be increased by securing a sleeve therearound, such as illustrated in Figure 7 by the sleeve 49 applied to the spindle 22.

From the foregoing it will be readily apparent that the belt 46 will be driven when the drill 10 chuck 45 is revolved at different speeds depending upon the speed of rotation of said drill chuck and as variably controlled by the conventional speed change pulleys of the drill press. The end table 17 may be utilized to support a workpiece for 15 detailed sanding and finishing a rounded portion of small radii, by utilizing the portion of the belt 46 passing around the small spindle 22. By loosening the fastening 19 the table 17 may be tilted at different angles for supporting a workpiece, not shown, for angle sanding and dressing.

Likewise, the side table 28 can be employed as 20 a rest for a workpiece for edge sanding utilizing the portion of the reach or flight of the belt 46 which is passing across the outer face 35 of the 25 backing plate 30, said backing plate preventing said belt reach from yielding inwardly and away from the workpiece. Likewise, the table 28 may be angularly adjusted for supporting a workpiece for angle sanding and dressing to various shapes. 30 Also, detailed sanding and dressing such as rounded corners of edges and faces of a workpiece may be accomplished where the workpiece is supported on the table 28 and said table is employed in conjunction with the groove 37 which 35 permits a portion of the belt flight or reach to yield inwardly, for rounding off corners and edges of the workpiece. The end of the table 28 located adjacent the larger belt pulley 41 may be employed in conjunction therewith for larger radii 40 sanding of rounded surfaces.

Furthermore, both tables 17 and 28 may be 45 raised and lowered for utilizing the entire width of the sanding belt 46. The diagonal joint 47 of the sanding belt 46 lessens vibration and tearing 50 of the belt which would otherwise occur due to the sudden jar of a straight joint moving into engagement with the small spindle 22 and which spindle would additionally tend to rupture a straight joint due to its short radius.

55 It will thus be apparent that substantially all types of radius and edge sanding of various materials may be effectively accomplished with the sanding attachment 10.

It will also be apparent that the sanding attachment could be utilized with a separate electric motor or an electric hand drill suitably supported rigidly above a workbench or the like to which the base plate 11 was clamped.

Various other modifications and changes are 60 contemplated and may obviously be resorted to, without departing from the spirit or scope of the invention as hereinafter defined by the appended claims.

We claim as our invention:

65 1. A belt sander attachment for a power tool having a rotary driven chuck disposed above a supporting table, comprising a base plate having one end adapted to rest on a table of a power tool, clamping means detachably securing said base plate end to the table, a spindle of small diameter, means supporting and journalling said spindle in substantially an upright position above an opposite end of said base plate, a drive pulley of larger diameter than said spindle adapted to be 70 detachably secured to a rotary chuck of the power

tool and supported thereby above the table and with the axis of the pulley disposed substantially parallel to the axis of said spindle, an endless sanding belt trained around said pulley and spindle and driven by rotation of the pulley, and a work supporting table adjustably supported on the base plate and outwardly of and adjacent a portion of the sanding belt.

2. A sander attachment as in claim 1, said work supporting table having a depending slotted bar, a standard fixed to and rising from the base plate, and a fastening extending through the bar slot and through said standard for adjustably securing the bar to the standard to support the table at different elevations relatively to the sanding belt and in different planes relatively to the plane of an adjacent portion of the sanding belt.

3. A belt sander attachment as in claim 2, a backing plate, means detachably and adjustably supporting said backing plate above and substantially perpendicular to the base plate and between the belt reaches and with an outer face of the backing plate in engagement with one of the belt reaches, said belt reach extending between said backing plate and an adjacent edge of the workpiece supporting table.

4. A belt sander attachment as in claim 3, said outer face of the backing plate having a groove extending from end-to-end thereof over which a longitudinal portion of said belt reach extends

10

20

25

30

and into which said portion of the belt reach is displaceable.

5. A belt sander attachment as in claim 1, said supporting and journaling means comprising an elongated support, means pivotally mounting said support above the last mentioned end of the base plate intermediate of the ends of said support for vertical rocking movement, said spindle being mounted on said support outwardly of the pivot thereof, and an adjusting screw extending threadedly through an inner end of the support and bearing on the base plate for adjustably limiting swinging movement of the spindle in a direction toward said pulley.

6. A belt sander attachment as in claim 5, said workpiece supporting table having a slotted bar fixed to and depending therefrom, and fastening means detachably and adjustably securing said bar to an outer end of the rocking support for adjustably supporting the table for rocking movement with said spindle and for vertical and angular adjustment relatively to the spindle.

7. A belt sander attachment as in claim 6, said workpiece supporting table having an inner edge provided with a notch for accommodating said spindle and the belt portion passing therearound.

8. A belt sander attachment as in claim 1, said sanding belt having a diagonal joint.
